(57) **CLAIM**

The ornamental design for a jump rope simulator, as shown.

DESCRIPTION

FIG. 1 is a front, elevational view of a first embodiment of a jump rope simulator showing my new design.

FIG. 2 is right side elevation thereof.

FIG. 3 is a top view thereof.

FIG. 4 is a bottom view thereof.

FIG. 5 is a perspective view thereof.

FIG. 6 is a front, elevational view of a second embodiment of a jump rope simulator showing my new design.

FIG. 7 is right side elevation thereof.

FIG. 8 is a top view thereof.

FIG. 9 is a bottom view thereof.

FIG. 10 is a perspective view thereof.

FIG. 11 is a front, elevational view of a third embodiment of a jump rope simulator showing my new design.

FIG. 12 is right side elevation thereof.

FIG. 13 is a top view thereof.

FIG. 14 is a bottom view thereof; and,

FIG. 15 is a perspective view thereof.
